CHARLES JAMES ROBERTSON, OF TAUNTON, MASSACHUSETTS, ASSIGNOR TO THE MIEHLE PRINTING PRESS & MANUFACTURING COMPANY, OF CHICAGO, ILLINOIS, A CORPORATION OF ILLINOIS.

FRONT SHEET-GUIDE FOR PRINTING-PRESSES.

1,161,251.

Specification of Letters Patent. Patented Nov. 23, 1915.

Application filed June 7, 1915. Serial No. 32,548.

To all whom it may concern:

Be it known that I, CHARLES JAMES ROBERTSON, a subject of the King of England, residing at Taunton, in the county of Bristol and State of Massachusetts, have invented certain new and useful Improvements in Front Sheet-Guides for Printing-Presses, of which the following is a specification.

This invention has to do with machines such as printing presses, folding machines and the like to which sheets as of paper are fed either automatically or by hand to be operated upon in accurate and unvarying register. In machines of this character it is usual to have side sheet-guides to fix the lateral register of the sheet and also front sheet guides to govern the location of the sheet longitudinally of the machine.

The present invention relates to the front sheet guide.

Hitherto front guides have been of either one of two classes, those in which the sheet contacting member of the guide moves substantially at right angles to the plane of the sheet, the guide moving up across the edge of the paper and allowing the sheet to pass underneath, and those in which the sheet contacting member moves in the general direction of the sheet travel but faster than the sheet until it is swung slightly out of the path of the latter.

The present invention relates to this second class of front guides and is particularly directed to the provision of means for supporting, adjusting and actuating the guides to obtain the most correct register through the extreme rigidity of construction thus made possible and through the reduction to a minimum of the weight of those parts that must start their movement suddenly and at high speed.

Heretofore the supporting rod for the guides has also been the force transmitting or actuating shaft. This has necessitated long, slender structures which must be oscillated very suddenly and at high speed and consequently with much vibration which latter precludes accurate registering. As heretofore arranged, to keep the moving parts light in weight has necessitated making the supporting rod of slender dimensions and loose in its bearings so that it may oscillate freely. According to this present invention the supporting rod may be and is

preferably, as shown, a massive bar rigidly fixed to the main frame of the machine itself while to this stationary supporting rod is firmly fixed in a state of rest the body of the guide which is firmly clamped in adjusted position both longitudinally and transversely of the machine. The actuating shaft, being separated entirely from the front guide and making physical contact with any part thereof only when and after the guide has accomplished its function of registering the sheet, may be as light as desired for quick action and may have as many additional bearings between the side frames as are needed, these bearings being rigidly supported from the fixed guide supporting rod. The member which bears the actual sheet-contacting surface of the front guide is thus made exceedingly light and this member is the only part that has to start from a state of rest as the speed of the paper; and all the spring required is such as is needed to control this small mass. The combating forces between the actuating means and the spring return are confined to a region closely adjacent the final sheet guiding point, and transmission stresses and strains are thus largely avoided in all the parts affecting register.

In order that the invention and its mode of application and operation shall be clear to those skilled in the art a preferred embodiment of the same is set forth for purposes of illustration in the accompanying drawing and in the description based thereon.

In the drawing—Figure 1 is a fragmentary transverse section through a portion of a printing cylinder showing one of the sheet guides in elevation; and Fig. 2 is a fragmentary front elevation of one end of the cylinder and guide.

One side of the main frame of the machine is represented at 11, it being understood that this framing consists generally of the two side frames with suitable base and cross ties spacing them apart so as to support the two ends of the cylinder shaft and any other shafts or rods extending across said frame. Suitably journaled in the two side frame members 11 is the shaft 12 of the cylinder 13 for clockwise rotation as represented in Fig. 1 by means of suitable gearing or other driving means not shown. This

cylinder is of the usual construction and is provided with sheet grippers 14 carried by the rocking gripper rod 15, the gripper rod being actuated by well known tumbler or 5 cam and spring arrangement so as to suddenly close upon the forward end of the sheet of paper and to release the same thereafter in proper timed sequence to the operation of the machine upon the sheet. The 10 feed board is indicated at 16, being rigidly supported and adapted to receive the sheets and to support the same as they are fed to the machine and into register with the front and side gages respectively. The metallic 15 front extension of the feed board is shown at 17 and to the underside thereof is the underguide 18 mounted upon the rod 19 for adjustment to the desired position transversely of the press, there being as many 20 underguides 18 as there are front guides.

The parts thus far described are of the usual character and form no distinctive part of the present invention which is adapted for use in connection with feeding mechanism cylinders and grippers of many types.

Suitably fixed in the side frame members 11 is the guide supporting rod 20 having therein a longitudinally extending V-shaped groove 21 within which engage the set screws 22 by means of which the rod 20 is fixed against rotation within the machine frame and which groove also serves, as will be hereafter described, for the adjustable mounting of the front guides upon the rod.

35 The actual sheet contacting surface by which the front edge of the sheet is registered is usually of hardened steel and is here shown as a plate 23 fastened by screws to the finger 24 pivoted to the body of the 40 guide at 25. The guide body comprises two side members 26, 26, slidably mounted upon the guide supporting rod 20. These two side members are spaced apart by the square shouldered stud 27 and, when clamped in 45 adjusted position, by the squared end 28 of the adjusting screw 29. Between these two side plate members is a hub 30 which is slidably mounted upon the supporting rod 20 but held from angular movement thereon by 50 the engagement within the groove 21 of the cylindrical gib 31 which lies lengthwise partially within the groove and partially within a rectangular key seat 32 of the hub 30. The clamping of the hub 30 in adjusted position longitudinally of the shaft 20 is accomplished by means of the set screw 33 which bears inwardly upon the cylindrical gib 31.

While it is desired to securely anchor the 60 guides upon the rod 20 to prevent angular movement thereon it is also necessary to provide for a slight angular adjustment of the guides in order to adjust the position which will be occupied by the contact surface of the guide plate 23 longitudinally of

the machine to vary the front margin of the sheet. To effect this adjustment of the front guide the same is angularly adjusted bodily by swinging the same about the axis of the rod 20 as a center. This will vary the front 70 margin of the sheet within a requisite range without materially affecting the angular relation of the plate 23 to the front edge of the sheet, this being due to the fact that the supporting rod 20 includes a radial plane 75 from the center of the cylinder within which plane lies the sheet contacting face of the guide plate 23, and the swing of the front guide about the axis of the supporting rod 20 will therefore be approximately tangent 80 to the cylinder 13 at the feed point within the extent of its range of adjustment and practically parallel to the sheet as it lies on the feed board and extension 16, 17. This adjustment is accomplished in the manner 85 following: The hand wheel 34 on the screw 29 has a boss 35 bearing upon a washer 36 which in turn bears upon an upward extension 37 of the hub 30. The squared end 28 of the screw 29 is normally rigidly clamped 90 between the side plate members 26 by means of the bolt 38 whereby the body of the guide is rigidly connected with the frame of the machine through the hub 30 and the supporting rod 20. Upon the loosening of the 95 nut 39 of the bolt 38 the clamping action of the plates upon the hub 30 and upon the squared end 28 of the nut of the screw is relieved to such an extent that by the manipulation of the hand wheel 34 the plates and hub may be angularly moved relative to each other resulting in the swinging of the 100 guide bodily about the axis of the supporting rod 20 as a pivot and thus adjusting the sheet contacting plate 23 in an arc which is tangent to the cylinder at the point of feed and substantially parallel to the plane of the sheet lying upon the feed board.

The guide finger 24 pivoted at 25 is yieldingly held in the position shown against 110 abutments 26^a on the side plate members 26 by the compression spring 40 on a rod 41 which is pivoted at 42 to the said guide finger 24, said rod 41 being guided at its opposite end in the squared stud 27.

115 The guide-actuating shaft 43 is journaled in bearings of the machine frame at 44 so as to rock freely at the proper time and it may be provided with additional bearings as indicated at 45 intermediate the two sides of 120 the frame. These intermediate bearings being rigidly supported upon the fixed rod 20. Upon this actuating shaft 43 is mounted a series of tappet arms 46 for slidable adjustment longitudinally of the shaft by means 125 of opposed grooves within which is mounted a key 47 which is confined within the grooves between the two side plates 26 whereby the tappet arm 46 slides longitudinally of its shaft 43 together with the side plates and 130

hub of the guide body without disturbing the angular fixed relation between the tappet arm 46 and its shaft 43, the one set screw 33 being thus utilized to clamp the entire 5 guide mechanism in longitudinal adjustment upon the shafts 20 and 43.

The tappet arm 46 carries at its free end a roller 48 which is adapted to engage, upon the rocking of the shaft 43, with a projection 49 of the guide finger 24. The position at rest of the tappet arm 46 and the finger extension 49 is such that there is a considerable distance between the said extension 49 and the roll 48 which allows for the arm 10 and roll to have reached its maximum speed of angular swing together with the shaft 43 before it contacts with the extension 49 in order that the contact plate 23 of the guide finger 24 shall move at the proper time suddenly and at the requisite speed to clear 15 the path of the sheet after registration.

The shaft 43 is actuated by means of a cam 50 which is fastened by means of a bolt 51 screwed into the end of the cylinder 13 20 within a slot 52 of the cam 50 so that the timing of the cam 50 may be regulated. This cam 50 acts upon a roll 53 on a stud 54 at the front end of an arm 55 which is rigidly secured to the actuating shaft 43 so 25 that the said shaft 43 will be rocked in properly timed relation to the feed of the sheets whereby to effect the front registration of the sheet and the withdrawal of the front 30 guide from before the sheet at the proper time so as to permit the passage of the sheet thereunder.

From the foregoing it will be seen that, in addition to the advantageous constructional features heretofore pointed out, reaching to 40 the attainment of rigidity and quickness of response to the actuating forces, the invention presents further advantages over the prior art.

Heretofore it has been usual to withdraw 45 the front guide previous to the grasping of the sheet by the grippers and front drops or "grass-hoppers" have been used to hold the sheet in position on the feed plate in the interval therebetween, thus necessitating additional mechanism without even then entirely avoiding danger of disarrangement of the registered sheet. My invention above described entirely eliminates this uncertainty by permitting the grippers to seize the sheet 50 immediately after the registration of the latter and while yet held against the front guides, which guides move forwardly away from and upwardly out of the path of the sheet, while it is advancing in the grasp of the 55 grippers. This forward and upward movement of the guide, about its axis 25, which is substantially in the radial plane of the cylinder passing through the point of sheet registration and at a higher speed than that 60 of the paper, avoids the dragging of the

guide face transversely across and in contact with the edge of the sheet with the consequent danger of disturbing the position of the registered sheet.

I claim:

1. In a machine of the character described, a front sheet-guide mechanism comprising a stationary supporting rod extending longitudinally of the cylinder, a plurality of front guides supported by the rod and including sheet-contact fingers mounted for independent movement into and out of the path of the sheet, yielding means to hold the fingers normally in the path of the sheet, and means mounted independently of the supporting rod and adapted to engage the contact fingers to actuate the same, and means controlled by the operation of the press to act upon the actuating means whereby to withdraw the sheet contact fingers and permit the sheet to be advanced by the grippers. 70 75 80 85

2. In a machine of the character described, a front sheet-guide mechanism comprising a guide-supporting rod extending longitudinally of the cylinder, a plurality of front guides supported by the rod and adjustable bodily about the axis thereof and including sheet contact fingers pivoted for independent movement thereof into and out of the path of the sheet, yielding means normally holding the contact fingers in the path of the sheet, tappet members mounted independently of the guide supporting rod and adapted to engage the fingers, and means to 90 95 100 105 actuate the tappet members in timed relation to the operation of the press whereby to withdraw the sheet contact fingers and permit the sheet to be advanced by the grippers.

3. In a machine of the character described, a front sheet-guide mechanism comprising a guide supporting rod rigidly mounted in the machine frame and extending longitudinally of the cylinder, a plurality of front guides mounted on the rod for bodily adjustment longitudinally of the rod and about the axis thereof and including sheet contact fingers pivoted for independent movement in an arcuate path, 110 springs normally holding the contact fingers in the path of the sheet fed to the machine, tappet members mounted independently of the guide supporting rod and adapted to engage the fingers, and means to actuate the tappet members in timed relation to the operation of the press whereby to withdraw the sheet contact fingers and permit the sheet to be advanced by the grippers. 115 120

4. In a machine of the character described, a front sheet-guide mechanism comprising a guide supporting rod rigidly mounted in the machine frame and extending longitudinally of the cylinder in a radial plane including the points of engagement of 125 130

the sheet by the grippers, a plurality of front guides mounted on the rod for bodily adjustment longitudinally thereof and about the axis thereof and including sheet contact fingers pivoted for independent movement in an arcuate path tangential to the cylinder surface, springs normally holding the contact fingers in the path of the sheet fed to the machine, tappet members mounted independently of the guide supporting rod and adapted to engage the fingers, and means to actuate the tappet members in timed relation to the operation of the press whereby to withdraw the sheet contact fingers and permit the sheet to be advanced by the grippers.

5. In a machine of the character described, a front sheet-guide mechanism comprising a stationary guide-supporting rod extending longitudinally of the cylinder, a plurality of front guides supported by the rod and adjustable bodily about the axis thereof and including sheet contact fingers pivoted for movement independently thereof into and out of the path of the sheet, yielding means normally holding the contact fingers in the path of the sheet, a rock shaft journaled in the machine frame parallel to the guide supporting rod, tappet arms carried by the rock shaft and adapted to actuate the contact fingers upon the rocking of the shaft, and means to rock the shaft in timed relation to the operation of the machine whereby to withdraw the sheet contact fingers and permit the sheet to be advanced by the grippers.

6. In a machine of the character described, a front sheet-guide mechanism comprising a guide supporting rod rigidly mounted in the machine frame and extending longitudinally of the cylinder in a radial plane including the points of engagement of the sheet by the grippers, a plurality of front guides mounted on the rod for bodily adjustment longitudinally thereof and about the axis thereof and including sheet contact fingers pivoted for independent movement in an arcuate path tangential

to the cylinder surface, springs normally holding the contact fingers in the path of the sheet fed to the machine, a rock shaft 50 journaled in the machine frame parallel to the guide supporting rod, tappet arms carried by the rock shaft and adapted to actuate the contact fingers upon the rocking of the shaft, and means to rock the shaft in 55 timed relation to the operation of the machine whereby to withdraw the sheet contact fingers and permit the sheet to be advanced by the grippers.

7. In a machine of the character described, a front guide mechanism comprising a stationary supporting rod extending longitudinally of the cylinder, front guides supported by the rod normally in the path of the sheet, guide-actuating means mounted 65 independently of the supporting rod and arranged to engage the guides at predetermined intervals to move the same out of the path of the sheet as the latter is advanced by the grippers.

8. In a machine of the character described, a front guide mechanism comprising a supporting rod extending longitudinally of the cylinder, front guides supported by the rod and including sheet contact fingers pivoted for independent movement in an arcuate path tangential to the cylinder surface, the pivotal axis of the fingers lying substantially in a radial plane including the cylinder axis and the points of engagement 75 of the sheet by the grippers, yielding means holding the fingers normally in the path of the sheet, guide-actuating means mounted independently of the supporting rod and arranged to engage the guides at predetermined intervals to move the same forwardly and outwardly out of the path of the sheet as the latter is advanced by the grippers.

In testimony whereof I have hereunto signed my name in the presence of a sub- 90 scribing witness.

CHARLES JAMES ROBERTSON.
